WRAPPER FOR PIES

Charles J. Westin and William G. Sperr, Philadelphia, Pa.

Application September 10, 1931, Serial No. 562,134

1 Claim. (Cl. 206—44)

This invention relates to a sanitary self-contained and protective wrapper for baker's pies and similar food products and has for its object the production of a simple and efficient covering 5 or wrapper which will be economical, practical and at the same time have an appearance pleasing to the eye.

Another object of this invention is the production of a simple and efficient covering or wrapper 10 for a pie or similar product, wherein the covering or wrapper is held in firm engagement with the container by folding or rolling the edge of the wrapper over the edge of the container, and without the necessity of employing other securing 15 means.

With these and other objects in view, the invention consists in certain novel constructions, combinations and arrangement of parts, as will be hereinafter more fully described and claimed.

20 In the drawing:—

Figure 1 is a top plan view of the container with the wrapper secured thereto, and partly broken away to show the position of the container and the relative position of the pie or other food 25 product.

Figure 2 is a section taken on line 2—2 of Figure 1.

Figure 3 is a bottom plan view of a portion of the container showing the manner in which the 30 wrapper is rolled under the edge of the container for holding the covering or wrapper in position.

Figure 4 is a transverse sectional view through a container showing a modified form or manner 35 of securing the wrapper or covering under the edge of the container.

By referring to the drawing it will be seen, for the purpose of illustration, that 1 designates a container in the nature of a pie plate, having diverging side walls 2 and terminating in a beaded outer edge 3. The pie or other food product 4 is placed within the container 1 as shown clearly in Figure 2 and over the top of the container and food product placed therein, is placed 45 a sheet of transparent glossy material, such as transparent paper, cellophane, glassine, or similar material, indicated by the numeral 5. This transparent strip of paper 5 has its ends projecting well over the beaded portion 3 of the container 1 and the edges or ends of the paper are then preferably rolled or coiled under the beaded portion 3 of the container 1 to produce a coiled 50 retaining band 6, which snugly fits under the beaded portion 3 of the container 1 and holds the transparent paper 5 snugly over the top of

the container and over the top of the food product 4.

While it is preferred that the transparent sheet 5 be held in engagement with the container 1 through the medium of the coiled band 6 as illustrated and previously described, and while this has been found to be a preferable way, it is not desired to limit this particular application to this particular form of securing the transparent sheet 60 to the container, since the sheet may be folded at its edges as indicated at 7 in Figure 4 to fit against the inclined faces of the side walls 9 of the container 10 and under the bead portion 11 of the container 10 as shown in the modified form 65 in Figure 4.

This sheet 12, as shown in Figure 4, may be spun or folded back under the side edge and under the bead portion 11 of the container 10 in any suitable or desired manner to restrict the edges of the covering 12 and prevent the same from 70 accidentally pulling off from the top of the container. The principal feature which should be borne in mind, however, is that the spinning under, the coiling under, or tucking under, or folding back of the edges of the transparent sheet 75 80 will produce a retaining ring which may be pressed flat against the container if desired, the wrapper in this way constituting a self-containing closure for the container in which the food product is placed.

It should be understood that by using a package wrapped as described above and illustrated in the drawing, the baker will be enabled to manufacture and deliver a pure and wholesome product 85 to the customer without any danger of it becoming soiled or contaminated in transit.

By means of the invention as illustrated and described a better package is produced which is less expensive than any so far attempted and still has the following distinctive features:— 90

Sanitary, not touched by hand, as mechanical means may be provided for its manufacture;

Perfect covering and still elastic enough to permit the product to breathe and expand;

Transparent, permitting a visual inspection of 100 kind and nature of content;

Glossy surface of the neatly fastened wrapper giving a greater sales appeal;

Economical, minimum amount of wrapping used, no glue, adhesive or binding material required.

Heretofore, with few exceptions, pies and the like have been delivered by bakers to the retailer without any protective covering. A few bakers have placed their products in a special envelope 110

or bag which required an expensive hand operation and a few others wrapped the pie loosely, placed it on a plate so that the weight of the pie would hold the tucked in sides of the wrapper between the pie and plate, again others have wrapped both pie and plate, fastening the tucked under sides by means of some adhesive or binder to the bottom of the plate.

By means of the simple device illustrated, it will be seen that no adhesive or other securing means other than the wrapper itself is necessary to seal the upper end of the container.

It is a well known fact that food products such as pies and the like must not be confined in a closed container, but should be allowed to breathe, thereby permitting the vapors to escape. It is also the nature of this kind of product to grow the first few hours after being baked, and the wrapper must therefore be elastic and expand to take care of the growth.

It should be understood that certain detail changes in mechanical constructions may be employed without departing from the spirit of the invention, so long as these changes fall within the scope of the appended claim, and it is not desired to necessarily restrict the present application to the wrapping of food products alone, since the method and structure as well as process illustrated will be found applicable to a large variety of products, sizes and shapes of containers.

In actual practice it is preferable to moisten

the wrapper by means of a damp sponge or felt wick along the edge of the wrapper which extends outside of the rim of the plate. The edge may be moistened by means of a spray or atomizer or in any suitable or desired manner. In actual practice for certain kinds of wrappers, moisture alone is required to produce the curl with a satisfactory tenacity. In some instances, however, heat is also required and a heated curling ring may be employed to give the curl a permanent set. On the other hand, some wrapping material may only require heat to give the desired result.

Having described the invention, what is claimed as new is:

In combination with a container open at its top and having a bottom and walls rising therefrom and formed with an outstanding bead, a single transparent comparatively thin wrapper sheet with unpleated marginal portions, said sheet being stretched across the top of said container with its marginal portions projecting from the container and curled downwardly, inwardly, upwardly and outwardly to form a compact restricted portion fitting snugly about walls of the container against the under face of said bead whereby said wrapper will be held against accidental removal from the container and will constitute a shield for the open top of the container.
